SURFACE ANGLE INSPECTION TOOL

Leon A. Chelmo, 2621 Major Ave. N. 55422, and John E. Schuh, 5301 Georgia Ave. N., Minneapolis, Minn. 55428

Filed May 23, 1967, Ser. No. 7,235

Term of patent 14 years

U.S. Cl. D52—6
Int. Cl. D10—08

FIG. 1

FIG. 8

FIG. 3

FIG. 1 is a perspective view of the surface angle inspection tool.

FIG. 2 is a front elevational view thereof.

FIG. 3 is a rear elevational view thereof.

FIG. 4 is a top plan view thereof.

FIG. 5 is an elevational view of one end thereof.

FIG. 6 is an elevational view of the other end thereof.

FIG. 7 is a bottom plan view thereof, and

FIG. 8 is an enlarged detail sectional view thereof, taken at 8—8 in FIG. 2, and illustrating surface configurations.

The essential features of the design reside in the solid line portions of the drawing.

We claim:

The ornamental design for a surface angle inspection tool, as shown and described.
